UNITED STATES PATENT OFFICE.

JOHN H. WICHMANN, OF OLDENBURG, GERMANY, ASSIGNOR TO HENRY SCHRODER, OF SAME PLACE.

IMPROVEMENT IN BREECH-LOADING FIRE-ARMS.

Specification forming part of Letters Patent No. 40,151, dated September 9, 1863.

To all whom it may concern:

Be it known that I, JOHN H. WICHMANN, of Oldenburg, in the Province of the Grand Duke of Oldenburg, in Germany, have invented certain new and useful Improvements in Breech-Loading Fire-Arms; and I do hereby declare that the following is a full, clear, and exact description of the construction and operation thereof, reference being had to the accompanying drawings, making a part of this specification, in which—

Figure 1 represents a side view of a fire-arm as designed for army purposes, and Fig. 2 represents a longitudinal vertical section through the same, a portion of the gun in both figures being represented as broken away. Fig. 3 represents a cartridge which is designed to be used with the gun, and Fig. 4 a section through the same. Fig. 5 represents a cartridge for practice, it being made without a ball, and Fig. 6 a section through the same.

My invention consists in the manner in which I have arranged and combined the hinged breech-piece with the lever and locking mechanism, by which the breech of the gun may be readily opened to receive the cartridge, and securely closed and locked before the discharging of the gun.

To enable others skilled in the art to make and use my invention, I will proceed to describe the same with reference to the drawings.

A represents the stock, and B the barrel, of the gun.

C is the breech-piece, hinged to the barrel at a, so as to swing upward. This breech-piece carries the nipple b, and has a boss, c, which enters the rear of the barrel, so as to form a tight "hut-butt joint" connection therewith. It has also a portion, d, on its under side cut away, so as to form a recess for the mechanism that locks it down to catch into.

A lever, D, is pivoted to the side of the gun at e, which has at its forward end a sliding catch, f, to hold it firmly in place when it is locking down the breech-piece C. The pivot of this lever is a shaft, g, firmly united to and turning with the lever, and a portion of this shaft is cut away, as seen at h, so as to form with the cut-away portion or recess m of the breech-piece a locking mechanism when in

one of their positions, but which detach when in another of their positions.

On the lever D there is a cam-ledge, i, as also a cam, j, and when the lever is raised upward and drawn backward the cam j strikes against the under side of the pin k in the breech-piece, thus raising or starting up the said breech, which had been previously unlocked from stock or frame by the first part of the movement of the lever. After the breech-piece is started up a short distance by the lever, it is thrown farther back by the thumb or hand of the user, the pin k by this movement passing in behind the cam-ledge i. When the breech-piece is in this position, the cartridge may be inserted, and a reverse movement of the lever lets down the breech-piece to its seat and locks it there by means of the shaft g, the lever itself being locked down by the shooting-bolt f. Before raising the breech-piece the hammer E should be set at "half-cock."

The bayonet F is hinged at l to a projection, G, formed on the front under side of the barrel, and in this projection is formed a recess, H, into which a catch, n, on the bayonet takes when the bayonet is swung out into position to hold it there. When the bayonet is "unfixed," the bolt n is drawn out of the recess, and it will then swing back and lie close against the under side of the barrel, its point being caught by a sliding shield to hold it in its thus unfixed position.

There are two sights, o p, the former hinged toward the rear of the gun and projecting forward, and having a slide, q, upon it, which will stop and hold the sight at any of the adjusted or marked positions, 1, 2, 3, 4, &c., which represent various elevations of the gun for various distances; or this sight may lie down flat upon the barrel and the other sight, p, used, which is hinged and swings the reverse of that of o, this latter sight p having an adjustable sight-piece, r, upon it, and when used standing upright, as seen in Fig. 2.

The lock is an exceedingly simple one, it being composed of but four pieces—viz., the hammer E, the mainspring I, the dog J, and the trigger K. Its construction being distinctly shown in Fig. 2, further description of it is unnecessary.

The cartridge L, which I propose to use, is made of a metal case, s, for containing the

UNITED STATES PATENT OFFICE.

JOHN H. WICHMANN, OF OLDENBURG, GERMANY, ASSIGNOR TO HENRY SCHRODER, OF SAME PLACE.

IMPROVEMENT IN BREECH-LOADING FIRE-ARMS.

Specification forming part of Letters Patent No. 40,151, dated September 9, 1863.

To all whom it may concern:

Be it known that I, JOHN H. WICHMANN, of Oldenburg, in the Province of the Grand Duke of Oldenburg, in Germany, have invented certain new and useful Improvements in Breech-Loading Fire-Arms; and I do hereby declare that the following is a full, clear, and exact description of the construction and operation thereof, reference being had to the accompanying drawings, making a part of this specification, in which—

Figure 1 represents a side view of a fire-arm as designed for army purposes, and Fig. 2 represents a longitudinal vertical section through the same, a portion of the gun in both figures being represented as broken away. Fig. 3 represents a cartridge which is designed to be used with the gun, and Fig. 4 a section through the same. Fig. 5 represents a cartridge for practice, it being made without a ball, and Fig. 6 a section through the same.

My invention consists in the manner in which I have arranged and combined the hinged breech-piece with the lever and locking mechanism, by which the breech of the gun may be readily opened to receive the cartridge, and securely closed and locked before the discharging of the gun.

To enable others skilled in the art to make and use my invention, I will proceed to describe the same with reference to the drawings.

A represents the stock; and B the barrel, of the gun.

C is the breech-piece, hinged to the barrel at *a*, so as to swing upward. This breech-piece carries the nipple *b*, and has a boss, *c*, which enters the rear of the barrel, so as to form a tight "but-but joint" connection therewith. It has also a portion, *d*, on its under side cut away, so as to form a recess for the mechanism that locks it down to catch into.

A lever, *D*, is pivoted to the side of the gun at *e*, which has at its forward end a sliding catch, *f*, to hold it firmly in place when it is locking down the breech-piece *C*. The pivot of this lever is a shaft, *g*, firmly united to and turning with the lever, and a portion of this shaft is cut away, as seen at *h*, so as to form with the cut-away portion or recess *m* of the breech-piece a locking mechanism when in

one of their positions, but which detach when in another of their positions.

On the lever *D* there is a cam-ledge, *i*, as also a cam, *j*, and when the lever is raised upward and drawn backward the cam *j* strikes against the under side of the pin *k* in the breech-piece, thus raising or starting up the said breech, which had been previously unlocked from stock or frame by the first part of the movement of the lever. After the breech-piece is started up a short distance by the lever, it is drawn farther back by the thumb or hand of the user, the pin *k* by this movement passing in behind the cam-ledge *i*. When the breech-piece is in this position, the cartridge may be inserted, and a reverse movement of the lever lets down the breech-piece to its seat and locks it there by means of the shaft *g*, the lever itself being locked down by the shooting-bolt *f*. Before raising the breech-piece the hammer *E* should be set at "half-cock."

The bayonet *F* is hinged at *l* to a projection, *G*, formed on the front under side of the barrel, and in this projection is formed a recess, *H*, into which a catch, *n*, on the bayonet takes when the bayonet is swung out into position to hold it there. When the bayonet is "unfixed," the bolt *n* is drawn out of the recess, and it will then swing back and lie close against the under side of the barrel, its point being caught by a sliding shield to hold it in its thus unfixed position.

There are two sights, *o* *p*, the former hinged toward the rear of the gun and projecting forward, and having a slide, *q*, upon it, which will stop and hold the sight at any of the adjusted or marked positions, 1, 2, 3, 4, &c., which represent various elevations of the gun for various distances; or this sight may lie down flat upon the barrel and the other sight, *p*, used, which is hinged and swings the reverse of that of *o*, this latter sight *p* having an adjustable sight-piece, *r*, upon it, and when used standing upright, as seen in Fig. 2.

The lock is an exceedingly simple one, it being composed of but four pieces—viz., the hammer *E*, the mainspring *I*, the dog *J*, and the trigger *K*. Its construction being distinctly shown in Fig. 2, further description of it is unnecessary.

The cartridge *L*, which I propose to use, is made of a metal case, *s*, for containing the
